UNITED STATES PATENT OFFICE

162,853

SELF-PROPELLED LOADER

Le Grand H. Lull, Minneapolis, Minn.

Application April 3, 1950, Serial No. 8,942

Term of patent 14 years

(Cl. D14—3)

To all whom it may concern:

Be it known that I, Le Grand H. Lull, a citizen of the United States, residing at Minneapolis, in the county of Hennepin and State of Minnesota, have invented a new, original, and ornamental Design for Self-Propelled Loader, of which the following is a specification, reference being had to the accompanying drawings, forming part thereof.

Fig. 1 is a front perspective view of a self-propelled loader, showing my new design.

Fig. 2 is a similar view.

Fig. 3 is a rear perspective view, from the opposite side of the loader.

Fig. 4 is a top plan view.

The characteristic features of my design re-

side in the portions shown by means of full lines in the drawing.

I claim:

The ornamental design for a self-propelled loader, as shown and described.

LE GRAND H. LULL.
